CLAIM

The ornamental design for a firearm suppressor as shown and described.

DESCRIPTION

FIG. 1 is a perspective partial rear view of a firearm suppressor showing our new design.

FIG. 2 is a perspective partial front view thereof.

FIG. 3 is a side view thereof.

FIG. 4 is a side view thereof.

FIG. 5 is a rear view thereof.

FIG. 6 is a front view thereof.

FIG. 7 is a top view thereof; and,

FIG. 8 is a bottom view thereof.
